UNITED STATES PATENT OFFICE.

JEREMIAH MULLEN, OF ROCHESTERVILLE, ONTARIO, CANADA.

CAR-COUPING.

SPECIFICATION forming part of Letters Patent No. 357,496, dated February 8, 1887.

Application filed May 1, 1886. Serial No. 200,785. (No model.)

To all whom it may concern:

Be it known that I, JEREMIAH MULLEN, of Rochesterville, in the county of Carleton, in the Province of Ontario, in the Dominion of Canada, have invented new and useful Improvements in Car-Couplings; and I do hereby declare that the following is a full, clear, and exact description of the same.

My invention relates to automatic car-couplings, and has for its object the construction of a simple and efficient self-coupler.

Figure 1 is a perspective view showing the end of a car having my improved coupling applied and the link coupled. Fig. 2 is a longitudinal section of the draw-head, showing the coupling-pin raised. Fig. 3 is a bottom view of the draw-head.

A represents the car fitted in the usual way with a draw-bar, B, having a draw-head, C, D being the ordinary pin, and E the coupling-link. The draw-head is bell-mouthed and made of considerable depth, so as to present a large opening to the free end of the coupling-link of a car advancing to be coupled, and facilitate a sure entry. The throat of the draw-head only affords sufficient room for the link to lie in it snugly when coupled, and is continued into the draw-bar to accommodate a sliding block, F, which is adapted to be set forward by means of one of a pair of levers, F', one of which is placed on each side of the car, and are pivoted to the block F by means of a pin, f, projecting through a slot, b, in the under side of the draw-bar.

The coupling-pin is carried in a sliding frame, G, working in suitable grooves on the draw-head, the pin being provided with a collar, d, and eye d', and secured to the frame 40 lug g by a pinned bolt, d''. H is a rocking shaft journaled at a convenient height to the

rear of the car, and provided at each end with a lever-arm, h, and in the center with a downwardly-bent arm, which is suitably connected by a chain, h', or otherwise to the lug g of the frame G. A chain or other connection, I, may also be employed to operate the arm H' from the roof of the car.

My improved coupling operates as follows: The link is raised by pulling down one of the arms h or pulling up the chain I, thereby raising the frame G and the pin D. The block F is now moved forward by means of one of the levers F', and the under-cut end of the block will pass under the end of the pin D and carry the same, as shown in Fig. 2. A link, E, entering the mouth of the draw-head, will strike against the end of the block F and push it back, thereby removing the support of the pin D, which will instantly drop into the link and secure it.

I am aware of Patents Nos. 162,336, 218,466, and 267,531, and I do not broadly claim a sliding block, F, the levers F', guide-frame G, nor rocking shaft H; but

I claim as my invention—

1. The combination of the throated draw-bar B, wide-mouthed draw-head C, coupling-pin D, sliding-block F, levers F', frame G, rocking shaft H, connected with the frame G.

2. In a car-coupling, a sliding-block, F, in combination with pin f, fast in said block, slot b in the draw-head, through which said pin f projects, and levers F, pivoted to said pin.

3. The combination of the rocking shaft H, lever-arms h, downwardly-bent arm H, chain h', lug g, bolt d'', pin D, and guide-frame G.

JEREMIAH MULLEN.
